VELOCIPEDE NOISEMAKER

David C. Munro, R.R. 1, Box 309, West Chicago, Ill.

Filed Mar. 21, 1960, Ser. No. 59,792

Term of patent 7 years

(Cl. D90—1)

Fig. 1.

Fig. 3.

Fig. 2.

Fig. 4.

Fig. 5.

FIGURE 1 is a front perspective view of the velocipede noisemaker, showing my new design;

FIGURE 2 is a top plan view thereof;

FIGURE 3 is a sectional view along line 3—3 of FIGURE 1;

FIGURE 4 is a rear perspective view thereof; and

FIGURE 5 is a side elevational view thereof.

I claim:

The ornamental design for a velocipede noisemaker, substantially as shown.
